UNITED STATES PATENT OFFICE

2,454,012

SUSPENSION MEANS FOR COOLING UNITS

Edward Oneal Sears, Oakland, Calif., assignor to
Colvin-Templeton, Inc., Oakland, Calif., a cor-
poration of California

Application January 12, 1945, Serial No. 572,544

6 Claims. (Cl. 248—311)

1

The present invention relates to improvements in suspension means for a cooling unit, and its particular object is to provide a suspension means of the character described which is simple in construction and greatly facilitates the act of suspending a cooling unit from a ceiling or the like.

My invention has particular reference to cooling units used in walk-in boxes, that is, relatively large rooms used for storing of meats, vegetables, fruits, or any generally perishable foods. Cooling units of this type are usually of considerable dimensions and of heavy weight, and the act of suspending the same from the ceiling of the walk-in box under present methods is an awkward task and requires the cooperation of several attendants, the ceiling usually being above man's height.

In the present invention it is proposed to provide a suspension means which greatly simplifies the operation of suspending the cooling unit and which allows one man to perform the operation in normal installations.

It is further proposed to provide a suspension means of the character described which allows the fastening of the unit in position to be performed from the outside of the unit, so that the latter may be completely assembled before installation.

And finally it is proposed to provide a suspension means for the unit that is particularly adapted to firmly anchor the unit to the ceiling, without any chance of any parts working loose.

Further objects and advantages of my invention will appear as the specification proceeds and the novel features of my means for suspending a cooling unit from a ceiling or the like will be fully defined in the claims hereto appended.

The preferred form of my invention is illustrated in the accompanying drawing, forming part of this application, in which:

Figure 1 shows, in side elevation, two cooperative members, adapted for fastening to the ceiling and the unit respectively, in an intermediate position of the installing operation;

Figure 2, a vertical section through an installed unit;

Figure 3, a bottom plan view of the two members in assembled relation; and

Figure 4, an end view of the two members.

While I have shown only the preferred form of my invention, I wish to have it understood that various changes or modifications may be made within the scope of the claims hereto attached without departing from the spirit of the invention.

2

Referring to the drawing in detail, the cooling unit 1 may be of any conventional construction, is square in horizontal cross-section, and comprises in its general features an open box structure comprising four angular corner pieces 2 arranged in the four corners of the box, a drip pan 3 joining the corner pieces near or at the bottom and a top plate 4 joining the corner pieces at their upper ends by any suitable means.

The unit thus presents a square box with large openings 5 in the four sides thereof.

A conventional coil 6 is provided inside the box for carrying a refrigerant, and winds in a number of turns along the walls of the box, certain sections of the coil being exposed along the box openings while other sections are hidden behind the corner pieces. The exposed portions are preferably made of conventional brush type construction to present large radiating surfaces.

The drip pan 3 has a central opening 7 in which is mounted a conventional fan 8 driven by the motor 9 supported in the box in any suitable manner.

The top plate 4, which stretches across the top of the box, has two depending flanges or rails 10 and 11 which project downwardly, in the planes of the side walls, to within fairly close proximity of the coil sections.

This top plate 4 with its flanges serves as part 30 of a suspension means, and is made for cooperation with a second plate 12 attached to the ceiling as indicated at 13.

The plate 12 has two depending flanges 14 and 15 and is slightly longer than the plate 4, so as 35 to allow the plate 4 with its flanges to nest in the plate 12 with its flanges, with the flanges in frictional contact.

The flange 14 of the ceiling plate is formed with an inwardly projecting ledge 15, and the latter has a toe 16 rising from its inner edge.

The width of the flange 10 on plate 4 is such that the flange 10 fits between the plate 12 and the ledge 15. The flange 11 of plate 4 is formed with a ledge 17 and a toe 18 similar to those of the flange 14.

All of the flanges are preferably formed with suitable registering bolt holes 19, and may be secured upon one another by bolts and nuts in a conventional manner.

The manner of using my invention will be readily understood from the foregoing description.

In order to install the unit, the operator merely raises the unit toward the ceiling in tilted position, as in Figure 1, hooks the flange 10 over the

toe 16 to come to rest on the ledge 15', and then swings the other end up for the flange 11 to bear against the inside of flange 19.

Possibly friction will hold the unit in place temporarily, or the operator may place a nail or bolt through two corresponding holes 19 for temporarily holding the unit. He may then proceed to permanently fasten the flanges upon one another, as by bolting or riveting or welding.

It will be noted that my method of installation is rendered very simple in this manner and may be readily carried out by one person who is strong enough to lift the unit.

I claim:

1. Means for suspending a cooling unit from a ceiling comprising a member adapted for securing to the ceiling and having a pair of downwardly projecting flanges, with a ledge on one of the flanges, and a pair of vertical rails on the cooling unit spaced to fit between the flanges in face-to-face relation therewith, whereby the cooling unit may be raised in tilted position for engagement of one of the rails over the ledge and may then be swung into horizontal position for bringing both rails into face-to-face relation with the flanges.

2. Means for suspending a cooling unit from a ceiling comprising a member adapted for securing to the ceiling and having a pair of downwardly projecting flanges, with a ledge on one of the flanges, and a pair of vertical rails on the cooling unit spaced to fit between the flanges in face-to-face relation therewith, whereby the cooling unit may be raised in tilted position for engagement of one of the rails over the ledge and may then be swung into horizontal position for bringing the rails into face-to-face relation with the flanges, the ledge having a toe along the inner edge to prevent slipping off the rail over the front edge of the flange during the assembling operation.

3. Means for suspending a cooling unit from a ceiling comprising a member adapted for securing to the ceiling and having a pair of downwardly projecting flanges, with a ledge on one of the flanges, and a pair of vertical rails on the cooling unit spaced to fit between the flanges in face-to-face relation therewith, whereby the cooling unit may be raised in tilted position for engagement of one of the rails over the ledge and may then be swung into horizontal position for bringing the rails into face-to-face relation with the flanges, the flanges and the rails on the ledge side being substantially the same depth and of

a length greatly in excess of their depth to preclude lateral tilting and slipping of the cooling unit during the installing operation.

4. Means for suspending a cooling unit from a ceiling comprising a pair of flanges projecting downwardly from the ceiling, with a ledge on one of the flanges, and a pair of vertical rails on the cooling unit spaced to fit between the flanges in face-to-face relation therewith, whereby the cooling unit may be raised in tilted position for engagement of one of the rails over the ledge, and may then be swung into horizontal position for bringing both rails into face-to-face relation with the flanges.

5. Means for suspending a cooling unit from a ceiling comprising a pair of flanges projecting downwardly from the ceiling, with a ledge on one of the flanges, and a pair of vertical rails on the cooling unit spaced to fit between the flanges in face-to-face relation therewith, whereby the cooling unit may be raised to tilted position for engagement of one of the rails over the ledge, and may then be swung into horizontal position for bringing both rails into face-to-face relation with the flanges, the ledge having a toe along its inner edge to prevent slipping off the rail over the front edge of the flange during the assembling operation.

6. Means for suspending a cooling unit from a ceiling comprising a pair of flanges projecting downwardly from the ceiling, with a ledge on one of the flanges, and a pair of vertical rails on the cooling unit spaced to fit between the flanges in face-to-face relation therewith, whereby the cooling unit may be raised in tilted position for engagement of one of the rails over the ledge, and may then be swung into horizontal position for bringing both rails into face-to-face relation with the flanges, the flanges and the rails on the ledge side being substantially the same depth and of a length greatly in excess of their depth to preclude lateral slipping and tilting of the cooling unit during the installing operation.

EDWARD ONEAL SEARS.
